2,574,397

DEVICE FOR CONTROLLING THE OPERATION OF ELECTRIC SWITCHES

Donald Mayer King, Hitchin, England

Application December 5, 1950, Serial No. 199,166
In Great Britain December 22, 1949

5 Claims. (Cl. 74—501)

1

This invention relates to electric switches of the kind which are adapted to be mounted in an elevated position and to be actuated through the medium of a rocker arm or the like which is in turn operated by means of cords or the like which depend therefrom.

It is the object of the invention to evolve a single handle or grip member to which the two operating cords associated with a switch of the type referred to may be attached, such handle being so constructed and arranged that either of said cords may be operated as required by any person grasping said handle or grip member.

According to the invention the handle or grip member comprises a first member to which one operating cord may be attached, a second member to which the second cord may be attached, said two members being capable of sliding movement relatively to each other, resilient means adapted normally to couple said members together and capable of returning them automatically to predetermined relative positions after sliding movement, and means operable at will to prevent relative sliding movement of said members when required. Preferably the handle or grip member comprises an outer casing to which one cord is attached, a member disposed within said casing and slideable axially relatively thereto and to which the second cord is attached, means operable to prevent sliding movement of said member relatively to the casing when required and means adapted to return the parts to their original positions on those occasions when relative movement has taken place.

In order that the invention may be more clearly understood and readily carried into effect the same will be hereinafter more fully described with reference to the accompanying drawing which shows a section taken longitudinally through a handle or grip member.

Referring now to the drawing it will be seen that the handle or grip member comprises an outer casing 10 of cylindrical form which is adapted to house a piston or plunger member 11 the latter being so dimensioned that it is capable of an axial sliding movement within and relatively to said outer casing. Disposed within the piston or plunger member 11 is a coil spring 12 which is anchored at one end to a cap 13 serving to close one end of the casing 10 and at the other to a pin 14 carried by said member 11. Mounted externally of the casing 10 is a resilient trigger element 15 in the form of a leaf spring said trigger element having a projecting portion or nose 16 which is adapted on depression of the element to

2

be projected through a slot or aperture 17 in the wall of the casing 10 and to engage the head of the piston or plunger member 11 thereby to prevent axial movement of the latter relative to the casing. In the drawing the trigger element 15 is shown in full lines in its normal or inoperative position and in dotted lines in the depressed or operative position.

The handle or grip member is adapted to be attached to two cords which depend from a rocker arm coupled to a switch the arrangement being such for example that when one cord is pulled downwardly the rocker arm will be moved to effect closure of the switch, while when the other cord 15 is pulled said arm will be restored to its initial position thereby moving the switch to the "off" position. In certain circumstances the switch to be controlled may be of the self-return type the arrangement being such that upon cessation of a 20 downward pull on one or other of the cords, said switch will return automatically to its initial or "off" position.

In the drawing the cords above referred to are designated 18 and 19 and it will be seen that the 25 cord 18 is attached to the piston or plunger member 11 while the other cord 19 is attached to a bracket or projection 20 formed on the casing 10.

The arrangement is such that with the switch (to the rocker arm of which the cords 18 and 19 are attached) in the "off" position the cord 19 attached to the outer casing, will be slack while the cord 18 attached to the piston or plunger 11, will be fully extended and will support the weight of the handle or grip member. In this arrangement when it is required to operate the switch the trigger element 15 will be depressed to prevent axial movement of the casing 10 relatively to the piston or plunger member 11 and the handle or grip member as a whole will be pulled downwardly 40 thereby to exert a pull on the cord 18 which serves to move the rocker arm and thereby to actuate the switch. The slack on the cord 19 will be sufficient to ensure that downward movement of the handle or grip member and the corresponding 45 angular movement of the rocker arm to which said cord 19 is attached will not be impeded or prevented by the latter, the arrangement being such however that following actuation of the switch as above described the slack on the cord 19 will be taken up. On release of the handle or grip member the trigger element 15 will return to the inoperative position and the piston or plunger member 11 to which the cord 18 is attached will be retained by the spring 12 in its 55 retracted position. When the handle is again

pulled downwardly again to operate the switch the cord 19 which is attached to the casing 10 will be operative to move the rocker arm while the cord 18 will be pulled upwardly due to the actuation of said arm. Upward movement of the cord 18 is allowed by virtue of the fact that the piston or plunger member 11 can slide relatively to the casing 10, the trigger element 15 not being depressed on this occasion. The axial movement of the member 11 will serve to tension the spring 12 the arrangement being such that upon release of the handle or grip member the casing 10 and the plunger member 11, will be restored to their initial relative positions. The spring 12 is so chosen that it will have just sufficient tension to remain closed when the weight of the handle or grip member as a whole is supported by the cord 18 which is attached to the piston or plunger member 11.

While the handle or grip member according to the invention is particularly adapted for application to the operating cords for the switches of hoists and similar overhead equipment, its use is not necessarily limited thereto since it may obviously be applied in any case where two operating cords or the like are present which are required to be pulled alternately.

I claim:

1. A handle or grip member adapted to be attached to the operating cords of a switch of the kind referred to such member comprising a first member to which one operating cord may be attached, a second member to which the second cord may be attached, said two members being capable of sliding movement relatively to each other, resilient means adapted to couple said members together and capable of returning them automatically to predetermined relative positions after sliding movement, and means operable at

will to prevent relative sliding movement of said members when required.

2. A handle or grip member for attachment to the operating cords of a switch of the kind referred to such member comprising an outer casing to which one cord is attached, a member disposed within said casing and slidably axially relatively thereto and to which the second cord is attached, means operable to prevent sliding movement of said member relatively to the casing when required and means adapted to return the parts to their original positions on those occasions when relative movement has taken place.

15 3. A handle or grip member as in claim 2 wherein the means for preventing relative sliding movement comprise a depressible trigger element mounted externally of the casing and having a portion adapted on depression of said member to enter said casing through an aperture therein and to engage the slidable member.

4. A handle or grip member as in claim 3 wherein the trigger element comprises a leaf spring.

20 5. A handle or grip member as in claim 2 wherein the means for returning the parts comprise a spring which is anchored at one end to the casing and at the other to the slidable member.

DONALD MAYER KING.
